RICHARD BERGER, OF BONN-ON-THE-RHINE, GERMANY, ASSIGNEE TO FIRM F.
SOENNECKEN, OF BONN-ON-THE-RHINE, GERMANY.

COPYING MACHINE.

1,412,995.

Specification of Letters Patent. Patented Apr. 18, 1922.

Application filed November 28, 1913. Serial No. 803,591.

To all whom it may concern:

Be it known that I, RICHARD BERGER, a subject of the King of Bavaria, and resident at Bonn-on-the-Rhine, Venusbergweg 23, 5 Germany, have invented certain new and useful Improvements in Copying Machines, with means for cutting off sheets of any desired length.

The invention relates to a copying machine with means for cutting off sheets, of any desired length.

In the annexed drawings.

Fig. 1.—shows diagram of the copying machine.

15 Fig. 2.—a front elevation of the controlling mechanism.

Fig. 3.—shows a detail.

According to the invention, a screw driven by the machine is employed, having intersecting right and left handed screw threads. 20 In the grooves of these screw threads runs to and fro a tongue or shoe, which is turned by two stops one of which is adjustable so that the travel of the tongue can be prolonged or 25 shortened while the machine is in constant motion. The tongue is in this case reversed by the controlling element of the various auxiliary devices which should operate according to the length of the copying sheet 30 in each case.

The arrangement can be such that the tongue as soon as it arrives in the end position shall effect the control of all the auxiliary devices by the reversal of a single machine element. Since however under all circumstances a given shortest travel of the tongue must be taken as a basis the arrangement may be such that the several auxiliary devices are separately controlled by the 40 tongue at different points in its travel. Only those parts of the copying machine are shown which are necessary for a clear understanding of the arrangement. The web of paper p passes between the three rolls a , b , c and then proceeds to a cutting or separating device or to a reel. Above the roll a is mounted in bearings a screw 1 having intersecting right and left handed screw threads. The screw is driven by the shaft of the roll 50 a through spur wheel gearing 2, 3. A tongue 4, well-known per se, runs in the helical grooves (Fig. 3) and is provided with a cylindrical shank 5 mounted so as to be capable of rotation in a slide 6 which is 55 mounted so as to be capable of sliding upon

a bar 7 rigid with the frame. The shank 5 of the tongue has at its upper end a forwardly bent arm 5¹. As the slide 6 moves to and fro on the bar 7 the arm 5¹ strikes alternately a buffer spring 8 located on the 60 left hand of the machine and a like spring 9 located on the right hand of the machine. The latter spring is mounted upon a slide 10 adjustably arranged upon a rail 11 provided with a graduated scale adapted to indicate 65 the length of a sheet of paper separated by a cutting device for example.

The slide 6 is provided with another striking piece 12 by which, when in the extreme left hand position, it engages with the end 70 13¹ of a rod 13 capable of sliding endwise in the frame of the machine. The rod 13 rests normally under the influence of a spring 14 but is moved to the left by the slide 6, 12 in order to set in motion or in 75 general to govern in any suitable manner the auxiliary or secondary devices.

When the screw 1 is caused to rotate in the direction of the arrow shown in Fig. 2 the slide 6 being in the position indicated, 80 the tongue 4 by means of the left handed screw thread will be moved towards the right hand. This movement is continued until the arm 5¹ on the shank 5 strikes against the buffer spring 9. This spring is 85 thereby put under stress and reverses the tongue as soon as the latter arrives at the nearest intersection of the screw threads (see Fig. 3). The tongue in turning enters the right handed helical groove and is therefore moved towards the left hand. Towards the end of this movement, the striker 12 on the slide 6 pushes the rod 13, 13¹ towards the left. The arm 5¹ on the shank 5 is now 90 however again reversed by the left hand buffer spring 8 as soon as the tongue has arrived at an intersection of the screw threads and is in a position to permit this rotary movement. The series of movements then 95 recommence.

The arrangement can obviously be also carried out by making both the stops 8 and 9 controlling the tongue adjustable. In practice however it will be found sufficient if one of these two spring stops be made 100 adjustable. In order to control several auxiliary devices of the machine at different moments all that is required are corresponding controlling striking pieces formed substantially in a similar manner to the rod 13 110

which is normally at rest under the influence of a spring and distributed over the travel or stroke of the tongue 4 or of its shank 5 or its slide 6.

5 I claim:

1. In combination, a copying machine including a plurality of rollers and auxiliary devices, a shaft provided on its periphery with intersecting right and left hand screw threads, means between one of the rollers and the shaft for rotating the latter, a guide, a slide mounted on the guide, a pivoted shoe depending from the slide, means for partially rotating the shoe at the end of its 10 sidewise movement to cause it to register with the respective screw threads, and a 15 slidable trip in the path of movement of the slide and which is struck by the latter upon each complete reciprocation to start the auxiliary devices.

2. In combination, a copying machine including a plurality of rollers and auxiliary

devices, a shaft provided on its periphery with intersecting right and left hand screw threads, means between one of the rollers 25 and the shaft for rotating the latter, a guide, a slide mounted on the guide, a stem pivoted in the slide, the upper end of the stem having an extended portion, a shoe at the other end of the stem and which engages the 30 threads on the shaft, a resilient buffer in the path of movement of the extended portion of the stem, an adjustable buffer in the path of the extended portion of the stem, said buffers causing the stem to be turned to 35 change the position of the shoe in the threads, and a trip located in the path of the slide to start the auxiliary devices.

In testimony whereof I have hereunto set my hand in presence of two witnesses.

RICHARD BERGER.
